HIGH-PRESSURE RECIPROCATING PISTON COMPRESSOR

Application filed February 3, 1928, Serial No. 251,714, and in Switzerland June 8, 1928.

This invention relates to high pressure piston or reciprocating compressors or the like of the kind in which the working pistons of the compressor or their intermediate 5 pistons are actuated by driving pistons which are preferably exposed on both faces to the action of a column of liquid.

The output of such compressors has hitherto been limited by the dimensions of the last stage and not by the power of the driving apparatus, the dimensions of the last stage being themselves limited by the question of packing the working piston and stuffing boxes. In fact, as regards the latter there is a definite diameter, which if exceeded, cannot be efficiently packed with the means at present available.

The invention has for its object to provide an improved construction of such compressors in which these disadvantages are obviated and the output increased while simplifying the driving mechanism.

According to the present invention at least two driving pistons respectively actuate the individual working pistons of two or more compressor cylinders arranged in parallel for the purpose of increasing the output of the compressor whilst simplifying the driving mechanism. By the term "arranged in parallel," as used above and throughout the remainder of the description, is intended to be meant the arrangement of the cylinders whereby they operate in the same stage.

35 The liquid columns which act on the intermediate pistons of these cylinders are preferably all actuated by one and the same piston of the driving machine. The cylinders may be arranged in pairs and the intermediate pistons of each pair may be connected by a column of liquid disposed in the same plane as that in which is disposed the column of liquid connecting one of the pair of intermediate pistons and the corresponding piston of the driving machine.

40 Alternatively the liquid column between the intermediate pistons of each pair may be disposed in a plane either parallel to or transverse to the plane in which is disposed the liquid column between one of the pair

45

50

of intermediate pistons and the corresponding piston of the driving machine.

The arrangement of the cylinders which are in parallel may also be such that the working pistons of some are disposed below the piston of the driving machine while the working pistons of the others are disposed above the said piston. 55

A few constructional examples of the invention are illustrated diagrammatically by way of example in the accompanying drawings, in which

Figure 1 shows two stages, for example the two uppermost stages, of a piston compressor, in section on a central plane.

Figures 2, 4 and 6 show modifications of the arrangement of Figure 1.

Figure 3 shows a section on the line I—I of Figure 2, and

Figure 5 shows a section on the line II—⁷⁰
II or III—III of Figure 4.

In the construction illustrated in Figure 1 the movement of the liquid columns within the cylinders 8, 9 and 10 is effected by double-acting primary pistons 5, 6 and 7 mounted on a piston rod 4 which is connected to the crank 1 of the driving machine (not shown) through a crosshead 3 and connecting rod 2. In the cylinders 13, 14, 15 and 16 are provided the intermediate pistons 19, 20, 21 and 22, mechanically connected to the compressor pistons 23, 24, 25 and 26 respectively, which act on the medium to be compressed in the cylinders 27, 28, 29 and 30 of the second last stage. In the cylinders 11 and 12 of the last stage are mounted intermediate pistons 17 and 18 mechanically connected to the working or compressor pistons 31 and 32 of the compressor cylinders 33 and 34. Between the pistons 5, 6 and 7 of the driving machine and one face of each of the pistons 17, 18, 19, 20, 21 and 22 are provided liquid columns 35, 36, 37, 38, 39 and 40 respectively, and between the adjacent pistons 17 and 18, 19 and 20, and 21 and 22 are respectively provided liquid columns 41, 42 and 43. To the suction pipe 44 for the cylinders 27, 28, 29 and 30 of the second last stage are connected the suction valves 45, 46, 47 and 48, the delivery

ery valves 49 and 50 for the cylinders 30 and 29 of this stage being connected to the suction pipe 51 and the suction valve 52 for the cylinder 34 of the last stage of the compressor, whilst the delivery valves 53 and 54 for the cylinders 28 and 27 are connected to the suction pipe 55 and the suction valve 56 for the cylinder 33 of the last stage. The delivery pipe 59 for the last stage leads from the delivery valves 57 and 58 for the cylinders 34 and 33 to the point of consumption of the compressed gas. The liquid columns between the adjacent intermediate pistons are arranged in the same plane as the liquid columns between one intermediate piston and the corresponding piston of the driving machine.

The pistons 19, 20, 21 and 22 actuated by the pistons 6 and 7 of the driving machine, cause the compressor pistons 23, 24, 25 and 26 to act on the medium within the cylinders 27, 28, 29 and 30 respectively which are arranged in parallel, while the pistons 17 and 18 actuated by the piston 5 cause the compressor pistons 31 and 32 to act on the medium within the cylinders 33 and 34 respectively, which are also arranged in parallel.

The construction shown in Figures 2 and 3 differs from that shown in Figure 1 in that the piston of the driving machine is made in the form of a differential piston, of which the larger portion 60 acts on the intermediate pistons of the cylinders 61 and 62 of the sixth stage, while the smaller portion 63 actuates the intermediate pistons of the cylinders 64 and 65. The pistons 66 and 67 of the cylinders 64 and 65 of the last stage, actuated through the liquid columns 68 and 69 by the pistons 63 of the driving machine and connected by the liquid column 70, actuate the compressor pistons 71 and 72 of the cylinders 73 and 74 which are arranged in parallel. The pistons 75 and 76 (Figure 3) which, as shown in Figure 2, are actuated through the liquid columns 77 and 78 by the piston 60 of the driving machine and are connected by the liquid column 79, act in a similar manner on the compressor pistons of the cylinders 80 and 81 which are also arranged in parallel. The supply to the suction valves is effected by the pipe 82, whilst the discharge takes place from the delivery valves through the pipe 83.

Whereas in Figures 2 and 3 the liquid columns provided between the adjacent intermediate pistons are located in a plane parallel to that in which is disposed the piston of the driving machine, Figures 4 and 5 show a construction in which the axis 11 of the liquid column 86 between two adjacent intermediate pistons crosses the axis of the pistons 87 and 88 of the driving machine. The cylinders 89 and 90 are con-

sequently arranged in parallel, as are also the cylinders 91 and 92.

Figure 6 shows a construction in which the pistons 101 and 102 are located above, and the pistons 103 and 104 below the piston 105 of the driving machine. The cylinders 106 and 107 are arranged in parallel as are also the cylinders 108 and 109. The operation of the compressor depends, as in the previous examples, on the alternating action of the liquid column 110 actuated by the piston 105 of the driving machine and the connecting columns 111 and 112 located between the pistons 101 and 102, and 103 and 104 respectively.

The invention enables the output of the known type of compressor to be doubled in spite of the fact that the driving mechanism is considerably simplified whilst the plunger diameter may remain the same as before. The diameter of the stuffing boxes shown only diagrammatically does not become excessive and the reduction in the dimensions reduces the extent to which the packing heats up, so that frictional heat can be more readily dissipated. In addition expansion due to heat is reduced and the play between the piston and the packing elements is therefore less.

I claim:

1. In a high pressure reciprocating compressor, the combination with a positively actuated primary piston, of a plurality of intermediate pistons, a plurality of compressor pistons arranged in parallel and each actuated by one of said intermediate pistons, an oscillating column of liquid between one side of said primary piston and one of said intermediate pistons, an oscillating liquid column between the other side of said primary piston and another of said intermediate pistons, and an oscillating liquid column between said intermediate pistons.

2. In a high pressure reciprocating compressor, the combination with a plurality of positively actuated primary pistons, of a plurality of intermediate pistons, a plurality of compressor pistons arranged in parallel and each actuated by one of said intermediate pistons, an oscillating column of liquid between one side of each of said primary pistons and one of said intermediate pistons, an oscillating liquid column between the other side of each of said primary pistons and another of said intermediate pistons, and an oscillating liquid column between the first and last named of said intermediate pistons.

3. In a high pressure reciprocating compressor, the combination with a horizontally disposed positively actuated primary piston, of a plurality of vertically disposed intermediate pistons, a plurality of compressor pistons arranged in parallel and each actuated by one of said intermediate pis-

tons, an oscillating column of liquid between one side of said primary piston and one of said intermediate pistons, an oscillating liquid column between the other side of said primary piston and another of said intermediate pistons, and an oscillating liquid column between said intermediate pistons.

4. In a high pressure reciprocating compressor, the combination with a plurality of horizontally disposed positively actuated primary pistons, of a plurality of vertically disposed intermediate pistons, a plurality of compressor pistons arranged in parallel and each actuated by one of said intermediate pistons, an oscillating column of liquid between one side of each of said primary pistons and one of said intermediate pistons, an oscillating liquid column between the other side of each of said primary pistons and another of said intermediate pistons, and an oscillating liquid column between the first and last named of said intermediate pistons.

5. In a high pressure reciprocating compressor, the combination with a horizontally disposed positively actuated primary piston, of a plurality of vertically disposed intermediate pistons, a plurality of compressor pistons arranged in parallel pairs and each actuated by one of said intermediate pistons, an oscillating column of liquid between one side of said primary piston and one of said intermediate pistons, an oscillating liquid column between the other side of said primary piston and another of said intermediate pistons, and an oscillating liquid column between said intermediate pistons, said last named column being disposed in the same plane as said first named columns.

6. In a high pressure reciprocating compressor, the combination with a horizontally disposed positively actuated primary piston, of a plurality of vertically disposed intermediate pistons, a plurality of compressor pistons arranged in parallel pairs and each actuated by one of said intermediate pistons, an oscillating column of liquid between one side of said primary piston and one of said intermediate pistons, an oscillating liquid column between the other side of said primary piston and another of said intermediate pistons, and an oscillating liquid column between said intermediate pistons, said last named column being disposed in a plane parallel to that in which are disposed said first named columns.

7. In a high pressure reciprocating compressor, the combination with a horizontally disposed positively actuated primary piston, of a plurality of vertically disposed intermediate pistons, a plurality of compressor pistons arranged in parallel pairs above and below said intermediate pistons and each actuated by one of said intermediate pistons, an oscillating column of liquid between one side of said primary piston and one of said

intermediate pistons, an oscillating liquid column between the other side of said primary piston and another of said intermediate pistons, and an oscillating liquid column between the said intermediate pistons, said last named column being disposed in the same plane as said first named columns.

8. In a high pressure reciprocating compressor, the combination with a plurality of horizontally disposed positively actuated primary pistons, of a plurality of vertically disposed intermediate pistons, a plurality of compressor pistons arranged in parallel pairs and each actuated by one of said intermediate pistons, an oscillating column of liquid between one side of each of said primary pistons and one of said intermediate pistons, an oscillating liquid column between the other side of each of said primary pistons and another of said intermediate pistons, and an oscillating liquid column between the first and last named of said intermediate pistons, said last named column being disposed in the same plane as said first named columns.

9. In a high pressure reciprocating compressor, the combination with a plurality of horizontally disposed positively actuated primary pistons, of a plurality of vertically disposed intermediate pistons, a plurality of compressor pistons arranged in parallel pairs and each actuated by one of said intermediate pistons, an oscillating column of liquid between one side of each of said primary pistons and one of said intermediate pistons, an oscillating liquid column between the other side of each of said primary pistons and another of said intermediate pistons, and an oscillating liquid column between the first and last named of said intermediate pistons, said last named column being disposed in a plane parallel to that in which are disposed said first named columns.

In testimony whereof I have affixed my signature.

CHARLES SCHAER.
